UNITED STATES PATENT OFFICE

HARRY L. VAN ZILE, OF NEW YORK, N. Y.

VENTILATOR

Application filed June 20, 1928. Serial No. 286,943.

The present invention has reference to ventilating devices and relates particularly to the species thereof applicable to doors or the like, to afford ventilation thru the same.

5 Primarily, the object of the invention is to produce an improved device of the class aforesaid, wherein the opening by way of which the air currents pass, is divided into cell like passages, so constructed and arranged as to offer the least obstruction to the flow of air therethru; the currents in entering or leaving the ventilator are diffused by one or more closures movable at substantially right angles against the open ends of the air passages in 10 order to avoid disturbing direct drafts; the exterior edges or boundary limits of the closures and the partitions being disposed in offset relation, thereby preventing vision and passage of light in every direction.

15 A secondary object is to provide a device of the nature mentioned with a closure which, when shut, will effectively subdue encountered acoustic waves, thus hindering the transmission of sound from one room to another thru a door equipped with this ventilator.

20 A third object is the provision in a device of the type set forth, of means for holding a closure partly or fully retracted from the opening wherewith it is associated.

25 A fourth object is the production of a device of the character disclosed, adapted for insertion into an opening cut therefor in a door, without the use of molding or other extra trim ordinarily employed for such purposes.

30 A special object of the invention is to supply a device of the kind referred to, which shall be distinguished by its attractive appearance, affording as well full and unimpaired circulation of air therethru.

35 A general object is to furnish a device for the purposes stated which shall be strong and rigid altho composed of light material; 40 readily cleaned; easy and noiseless to operate; not liable to get out of working order; and capable besides of economical manufacture.

45 Other objects of the invention will in part be obvious and in part be brought out more

fully in a detailed description hereinafter contained.

The invention consists in the various combinations and subcombinations of elements, arrangements and interrelative disposition of parts, and peculiar features of construction pertaining to the improved device, as herein described and defined in the appended claims.

55 Practical embodiments of the invention are illustrated on the drawings hereto annexed and wherein:—

60 Figure I is a combined plan view and section of one exemplification of this improved ventilator, the section being taken on the line I—I of Fig. II, looking down thereon, with parts broken away;

65 Fig. II is an enlarged fragmentary front view, looking in an upward direction in Fig. I, certain parts being in section and other parts being omitted;

70 Fig. III is an enlarged cross-section, taken on the line III—III of Fig. 1, looking from the left toward the right, the parts being in extended or open relation;

75 Fig. IV is also an enlarged section taken on the line IV—IV of Fig. I looking from right to left, the parts being shown in closed or collapsed condition.

80 Fig. V is another enlarged section taken on the line V—V of Fig. I looking in the same direction as for the preceding figure, namely from right to left, the parts being illustrated in their closed position;

85 Fig. VI is a fragmentary rear elevation of a somewhat modified form of the invention, certain parts being broken away;

90 Fig. VII is a fragmentary top plan view of the modification shown in Fig. VI, the parts being depicted in open relation; and

95 Fig. VIII is a perspective view of a detail pertaining to a connection between the parts.

Succinctly outlined, the invention as it exists in the embodiments thereof, herein exemplified, comprises a flanged frame adapted for insertion into an opening provided therefor in a door to which it is applied, with the flanges of the frame overlying the door on its inner side. This frame is interiorly divided into a plurality of 100

unequal-size, endwise open cells, by longitudinal and transverse, straight sided partitions, disposed in parallelism with the air currents passing therebetween. One or more 5 closures cooperating with the open face or faces of the frame are movably connected therewith. The connections which carry the closures admit of the same being moved, either toward the frame to completely shut 10 off the flow of air, or else fully or partly away therefrom to graduate the flow, the movement of the closures taking place against the ends of the cells for the purpose of diffusing the currents and avoiding the disturbing influences of drafts. Even in full open or 15 extended condition, the offset relation of the closures' perimetral edges to those of the partitions, effectively obstruct vision and light rays at every angle and from either side 20 of the ventilator. A soft medium attached to the inside face of one of the closures serves while the latter is pressed against the adjacent face of the frame to deaden and exclude sound waves striking the ventilator.

25 Obviously, the greatest benefit will be derived from the invention by using it in its entirety after the manner hereinabove expressed, although it may be noted that an operative device of acceptable design may 30 be produced by employing a less number of parts with correspondingly diminished advantages. Further, it will be observed by experts familiar with inventions of analogous import, that the combined frame and 35 closures herein disclosed are susceptible of various modifications having the same end in view. Therefore, let it be understood that the annexed drawings are offered by the way of example only, and are not put forth as 40 representing the sole means of reducing the invention to practice.

Referring now to the before mentioned views for a detailed description of the invention, the same comprises a frame denoted 45 as a whole by the reference numeral "11" and composed of relatively narrow top and bottom, right and left side strips numbered 12, 13, 14 and 15, respectively, preferably of metal plate, such as sheet steel. Of these 50 strips, the top and bottom ones are considerably longer than the side strips so that an elongated, parallelogrammic box-shaped structure of constricted width and of comparatively shallow depth is formed. This 55 box frame is of suitable dimensions to be received in an opening cut therefor into or above the uppermost panel of a door A. The near, side edges of the top and bottom strips 12, 13, are extended upwardly and downwardly so as to constitute flange-like appendages 16, 17 respectively, adapted to overlie the face of the door at the inner or room side thereof. Obviously, any other means 60 which will locate the frame 11 relatively to the depth or thickness of the door A, can 65

equally as well be substituted for the flanges 16, 17.

Interiorly, frame 11 is divided up by lengthwise or crosswise running, unequally spaced partitions 21-22 and 23-24-25-26-27, into a plurality of endwise open, straight-sided cells B, C, D, E, F, G, H, J, K, L, M, N, P and Q of different sizes. From Fig. II which represents the lefthand, half portion of the frame in full size, it will be 75 noted that the upper and lower end cells, designated B and K, and substantially of the same dimensions, are about half the size of cells C and L. The proportions of the latter are again half or nearly so of cell D, 80 while lower cells M and N, separated by a sub-partition 29, together equal cell D in area. Cell E included between transverse partitions 26-27, is somewhat more than twice the size of cell D, while the lower tier of 85 cells P, Q, divided by subpartition 30 have each fifty percent of the area of cell E. The intermediate row of cells F, G, H and J, altho of the same length as the cells in the corresponding upper row, namely B, C, D and E, 90 have only about half of the vertical height of the latter. Interposed between partitions 24-25, is a rather narrow cell space or compartment R which reaches from the top to the bottom strip. The purpose of the aforementioned cells will be more fully hereinafter referred to. It will be understood, that the other or right hand portion of the frame will be arranged on the same order as the left 95 half just above described. And it is also plainly seen that by adding or leaving out, one or more of the middle cells E, J and P-Q, the said frame may be increased or shortened in length, to fit any particular size of door required.

The extremities of the three species of partitions, 21-22; 23-24-25-26-27; and 29-30, as well as the boundary strips 12-13 and 15-16, are bent over right angularly as indicated at 32, 33, 34 to form feet or flanges, by means of which all of these parts may be anchored in position, thru the agency of electric spot-welding, or by any other appropriate method of fastening. Where the various partitions cross one another, their intersections are oppositely notched out, as exemplified at 36, 37 (Fig. VIII), in order to fit one into the other and leave the edges thereof flush or even with the front and rear faces of the frame. The interfitting joints of the partitions taken in conjunction with the endwise anchoring thereof to the perimetral strips constituting the frame proper, is conducive of a very rigid and compact structure, 110 capable of being manufactured from light sheet material. By reason of the fact that all of the exterior and interior parts of which the frame is constructed are disposed in parallelism with the flow of the air passing 115 between them or thru the cells encompassed 120 125 130

thereby, no appreciable diminution of the flow takes place, such as for instance does occur when the partitions or vanes, as they may also be termed, stand in oblique or angular relation to the passing currents.

For the purpose of diffusing the air currents as they travel in either direction by way of the cellular frame, and to obviate direct air drafts from one room to another, as well as to obstruct undeviating rays of light and vision therethru, one or more closures 40, 41 are provided. These closures may, if desired, be made to cooperate with either, or both of the front and rear faces of the said frame, i. e. on opposite sides of the door. A convenient way of mounting the aforesaid closures or cover plates, so that they may be moved away from or up against the frame's faces, in graduated amounts, is clearly depicted in Figs. III and IV.

The means for carrying the closure plates 40, 41, may include upper and lower pairs of interconnected links 42-43, 44-45 respectively, disposed in sets of four each, spaced a short distance from the transverse ends of the frame 11. The links spoken of, are located between the partitions 24, 25, within the narrow vertical cells R. The upper portions of said partitions are provided centrally with aligned guides that may be in the nature of elongated apertures 47, wherein are slidably received the terminals of a stud 48, one for each of the said cells R. To the shanks of studs 48 are jointly pivoted the upper extremities of links 42-43, the lower ends whereof have hinge connections with oppositely arranged ears 50, 51, respectively, projecting inwardly from the closures 40, 41, in proximity to the bottom edges thereof. The lower extremities of the other pair of links 44, 45, are hinged together on pins 53 fixed in the middle of said partitions 24, 25, in close adjacency to the bottom strip 13 of the frame 11.

Slotted ears 56, 57 are attached to the same sides of the closures 40, 41; respectively, as the before mentioned ears, 50, 51 being substantially aligned therewith, but in contiguity to the top edges of the said closures. The upper limits of the lower pair of links 44, 45 are pivotally connected to ears 56, 57, while intermediately of their lengths these links are movably jointed by shouldered rivets 58, 59 to the upper links 42, 43 respectively.

By preference and as shown, a rod 61 is arranged to extend between the lower and outer ends of the links 42 pertaining to both sets thereof, at the front side of the frame 11. Said rod is adapted to be engaged by the interiors of downwardly open gaps 62 (Fig. III) wherewith the aforesaid ears 50 are formed. The latter, of which there may be several, as will be observed from Fig. I, are spaced at certain intervals apart along the

inner face of the front closure 40. The upper and outer extremities of the other set of links 44, are provided with headed studs 64 capable of entering the slots in the upper ears 56, which slots are also left endwise open, as denoted at 66. From the foregoing, it will be comprehended, that the front closure can be readily hooked onto or lifted off rod 61 and studs 64, for purposes of cleaning the frame cells. In order to prevent accidental disassociation of the gapped and slotted ears 50 and 56 from their attachments 61, 64, the entrances to the gaps 62 may be made slightly constricted so as to require urging over the rod 61, thus making it necessary to apply some force to free or disconnect the ears 50 from the said rod. The yielding connections of the lower and upper terminals of the links 43, 45 with the ears 51, 57, respectively, on the outer or rear closure 41, may optionally be made permanent, that is, not disconnectible, as no need exists for removing the closure last referred to. For this reason, the rearwardly projecting, outer extremities of the links 43, 45, may be jointedly connected to the upper and lower ears 57, 51 by shouldered and headed studs 67, 69 respectively, fixedly secured to the last named links.

At such times as pressure is applied, by an operator, against either one of the closures, in a direction against the frame, to move them from open to the fully closed position thereof illustrated by Figs. IV and V, the studs 48 to which the sets of links 42, 43 are pivoted, travel upwardly in the elongated guide apertures 47. Contemporaneously, the studs 64, 69 will also move in an upward direction within the slots of the ears 56, 57. By virtue of the construction shown and described, the movements of the front and rear closures 40, 41, towards or away from one another, always take place in planes parallel with the corresponding faces of the frame 11. Besides, these closures can be conveniently opened and closed in graduated amounts so as to permit more or less air pass thru the cellularly divided frame. In entirely open condition, the areas defined by the linear measurements of the perimetral edges of the closures multiplied by their distances away from the frame's faces, are such as to establish an air-flow capacity around the edges of the closure and between the latter and the frame considerably in excess of the air-flow capacity thru the said frame. Thus it will be comprehended, that practically no diminution of the flow of the air currents do occur in transit thru this ventilator. Still no direct drafts can reach the occupants of a room the door whereof is furnished with one of these devices. This is because the air flowing by way of the latter is forced for a short distance to follow the door before it enters and passes thru the frame. In issuing at the opposite side of the door, the air is spread up and

down as well as sidewise in every direction before it diffuses in to the room.

With the object of reinforcing and promoting rigidity of the rear closure plate 41, the same is channelled thruout its length, as indicated at 73. At the lateral extremities of the said closure, the channels or corrugations spoken of, are made to taper or converge into the plane of the plate proper, giving the closure a neat and finished appearance. On the face of the front closure 40 adjacent to its bottom edge, are provided one or more hollow, shell-like grips 74 that may be formed by striking up the same from the plate of which this closure is composed.

In order to provide clearances for the rod 61 in the forward edges of the full size transverse partitions 25, 26 and 27, the same are notched out as depicted at 75 (Figs. IV and V). By virtue of the reason that the sub-partitions 29, 30, are of less depth than the main divisions, the former do not require notching of their frontwise facing edges. The rod just above referred to, moves into and is received in said notches when the closures are shut tight. While two of such closures have been shown, it is entirely feasible to employ only one of them, preferably the front plate. The rear closure 41 and its carriers, namely the links 43, 45 may well be omitted, without detracting either from the operativeness or efficiency of the device, except that the cell forming partitions will be exposed from the door's exterior.

No matter at what angles or directions lines are drawn tangential to the perimentral edges of the closures, these lines will intersect one or more of the transverse and longitudinal partitions. Or stated in other words, one or the other of the aforesaid partitions will obstruct any and all lines of sight or rays of light, from either side of the device, thus rendering it impossible for a person standing outside of the door to look thru the ventilator into the room, or vice versa, irrespective of the position in which this person stands or occupies.

The reason why the partitions adjacent to the transverse extremities of the frame 11, are spaced closer together, making the end cells smaller in size than those in the middle, is because these end compartments are proportionately more exposed. It is readily understood that due to the considerably longer perimentral edges encompassing the end portions of the closures, it is much easier to see thru the ventilator, or for light to be visible therethru, at these points. Hence such partitions cannot be placed as far apart as those located in the central part of the device. Moreover, on account of the notches 75 occurring in the partitions 25, 26 and 27 for the rod 61, it has been found necessary to interpose the sub-partitions 29, 30, so as to posi-

tively exclude all rays of light and obstruct vision in every direction.

At 76, 77 are indicated that fins or ribs project inwardly of the narrow vertical cells R, from the partitions 24—25 defining the same. These fins serve to block vision thru the last named cells whether the closure-carrying linkages are wholly received therein or extended outwardly therefrom. It will be observed that the upper ends of ribs 76, 77, which are located in reversely offset disposition on opposite sides of the guide apertures 47, reach in parallelism therewith from a point about halfway between the extremities of the said apertures, downwardly within a short distance above the fixed hinge pins 53. The major part of each of the fins referred to, is obliquely disposed with respect to the perpendicular direction of the said guide 47, for the purpose of affording proper clearance between the inner side edges of links 45, 46, when the latter are in folded condition.

From an inspection of Fig. IV it will be observed the relative positions of the link 42 and the rib 47 (shown in dot-and-dash lines). A convenient way of producing the said ribs or fins is by slitting around three of their sides and bending them up at the fourth sides thereof, at substantially right angles to the flat faces of the strips whereof the partitions 24, 25 are formed, in opposed relation, inwardly of the said cells R. The openings remaining in the said partitions after the fins in question have been struck up therefrom, do not in the least interfere with the light and sight obstructing properties of the aforesaid partitions.

The front closure 40 is preferably made in the nature of a shallow box with outstanding perimentral walls 78 surrounding its circumambient edges at the interior face thereof. Within walls 78 is received a flat dish-shaped frame 79 composed of a bottom (79) and sides 80. Inclosed by the latter and overlying the bottom is a thick piece of sheet felt 81, or other appropriate sound deadening material. The outer edges of frame-sides 80 are bent, as denoted at 82, inwardly over this material so as to retain the same in place. In a similar manner are the corresponding edges of the walls 78 folded over the first named side-edges 82, as represented at 83, to secure the interior frame 79 in its assigned position within the closure 40. At such times as this closure is pushed up against the frame 11, the felt facing 81 is forced into close contact with the flanges 16, 17 and the therewith flush edges of side strips 14, 15. The effect of this arrangement is that transmission of acoustic waves from side to side of the door thru the device is entirely subdued or prevented. Even rattling of parts occasioned by forceful shutting of the door, is quieted down to such an extent, by the felt packing, to make all vibrations of this kind

practically unnoticeable. Any desired means for retaining the frame 11 in position, may of course be employed, such for instance as suitable screws (not shown) entered into the material of which the door is made, thru appropriate openings provided therefor in one or both of the top and bottom strips 12, 13, of the said frame.

The exemplification of the invention given 10 by Figs. VI and VII, is practically the same as the previously described structure, except that certain details thereof have been modified as will hereinafter appear. Thus it will be seen that instead of having three rows of 15 cells in vertical height, this modification of the ventilator may be divided up into only two tiers, the upper and lower cells whereof, which are alike, being numbered C¹, D¹ and C², D² respectively. In place of individual 20 cellular compartments for the closure carrying linkage, the latter are disposed entirely on the outside of the door inserted frame 11^a. The top and bottom flanges 16^a, 17^a at the front face of the frame, as well as the single 25 closure 40^a employed in conjunction with this type of device, are considerably wider than the corresponding elements in the construction first above referred to. This is because closure 40^a alone has to perform the 30 same function as the double, or front and rear closure-plates 40 and 41. In this secondary form of the invention, the felt pad 81^a is held in position by over-lapping scalloped edges 82^a of the supplementary frame 35 79^a which is spaced inwardly from the perimetral walls 78^a around the primary closure 40^a.

In the space intervening between the last named walls and edges, is contained the linkage 40 by means of which the single closure is operably sustained from the frame 11^a. At each of the transverse extremities of the said closure is oscillatably mounted a link element 48^a, having rigid, double arms 49^a, 43^a, 45 provided at their ends with hook-shaped offsets 49 that are received in elongated guides 47^a attached to the front faces of the top and bottom flanges 16^a, 17^a. The offsets 49 are afforded a certain amount of play in a 50 lengthwise direction of the frame within said guides 47^a, while the body portion of element 49^a which partakes of a rocking motion, is retained in position by keepers 50^a fastened to the closure's inner transverse face. 55 Disposed in parallelism with the frame's longitudinal boundary strips, for instance the upper one 12^a, beyond the felt-pad containing frame 79^a so as to clear the same, and in right angular relation to the first mentioned element 48^a, is another link element 53^a. The latter is oscillatably carried by retainers 51^a from one of the flanges 16^a. The last named element, which also has the longer body portion, is in conformity with the shorter link element 48^a, formed with arms;

one whereof is indicated at 44^a. The extremity of this arm is provided with an offset 52 that is afforded limited travel within a guide 56^a affixed to the closure 40^a in proximity to the body portion of the element 48^a, as will be readily observed from an inspection of Fig. VI. The arms of the hereinabove referred to, right angularly arranged link-elements 48^a and 53^a, cooperate with their respective guides 47^a and 56^a, in such a manner, that not only is the single closure 40^a enabled to move into open or closed positions, but the movement of the said closure is always maintained parallel with the opposed flanges 16^a, 17^a. Fig. VII 70 illustrates the closure retracted from the door inserted frame 11^a, that is, in entirely open condition with respect to the cells C¹—D². By reason of the fact that the closure 40^a is suspended sidewise from the link-elements 75 specified, the weight of the former suffices to hold the latter in the position into which they are moved, by the operator manipulating the said closure.

In its broader aspects the invention herein disclosed is not limited to the precise features of construction and arrangement of parts shown and described, nor to any particular structural make-up or design by which it can be reduced to practice, as numerous changes may be made in the details without departing from the principles of the invention, or even sacrificing any of its chief 90 advantages.

Having now described my invention what I 100 claim as novel therein and desire to protect by Letters Patent of the United States is:—

1. A ventilator for doors or the like comprising a frame, a plurality of light-obstructing members interiorly of said frame, a closure structure including a frame-cover and disposed across the face of the frame for movement relatively to but wholly beyond the same, and means for reciprocably connecting said structure to the said frame, said means consisting of sets of lever elements connected directly to said closure and the frame, being projected beyond the latter in open position of the closure.

2. A ventilator for insertion in a door or the like comprising a rectangular frame, a plurality of spaced apart vision-preventing members within the latter, said members being disposed in planes parallel with sides of said frame, a closure co-operating with the spaces between the said members, and supporting means for said closure including reciprocal elements co-acting to maintain the closure always parallel to a given plane.

3. A ventilator for insertion in a door or the like comprising a rectangular frame, a plurality of members within the latter arranged to divide it into compartments of different sizes, of said compartments one near the centre of the frame is the largest, one

more remote from said frame centre is smaller, and one further away therefrom is still smaller, and a closure movable away from the said frame to open up the said compartments to the flow of air therethru, said closure being of greater size than the face of the frame to an extent at least sufficient to block all of said different size compartments to the passage of light thru the same, when the closure is moved into any of its compartment uncovering positions.

4. A ventilator for doors or the like comprising a rectangular frame, a plurality of vision obstructing members therewithin, said members being arranged in substantial parallelism with sides of said frame, a closure disposed across the face of the latter, and means hingedly carrying said closure at several places and restricting the movement thereof with respect to the frame to maintain the closure always parallel with the frame's face.

5. A ventilator, for doors or the like comprising a frame, a plurality of light obstructing members arranged in parallelism with sides of said frame, a closure disposed across the face of the frame, and means carrying said closure affording movement thereof in planes parallel with the frame's face, said means including a suspending element pivotally connected to the closure and covered thereby when the same is moved to abut the face of the said frame.

6. A ventilator for doors or the like comprising a frame provided with vision obstructing members interiorly thereof, a closure disposed across the face of said frame, and elements having pivotal and slidable connections with the frame and said closure arranged therebetween, a portion of said elements extending beyond the face of the frame when the closure is opened.

7. A ventilator for doors or the like comprising a frame provided with space apart light intercepting members interiorly thereof, a closure disposed across said frame and movable in parallelism toward and away from the face thereof, and a sound-deadening cushion carried by said closure and overlying a plurality of the areas included between said members when the closure is moved to maximum adjacency to the said frame.

8. A ventilator for doors or the like comprising a frame provided with spaced apart vision obstructing members interiorly thereof, a closure extending across the face of said frame and translationally movable toward and away therefrom, and a sound-deadening cushion carried at the inner side of said closure adjacent the face of the frame, said cushion being adapted to overlie said face and a plurality of the areas bounded by said members when the closure is moved to close the ventilator against the passage of air therethrough.

9. A ventilator for doors or the like comprising a frame provided interiorly thereof with spaced apart light intercepting members, a closure capable of covering the face of said frame and movable toward and away therefrom, and a sound-deadening cushion disposed at the inner side of said closure adjacent the frame adapted to cover its face and overlie a plurality of the spaces between said members upon being moved thereagainst the perimetral area between the edges of the closure and the surface of the frame, when the closure is fully open, being substantially greater than the face-area of the frame.

10. A ventilator for doors or the like comprising a rectangular frame provided interiorly thereof with vision preventing members, said members being disposed in parallelism with sides of said frame, and a closure mounted to extend across the face of the frame, said closure being parallelly movable toward and away from the frame and having a somewhat larger face area than the latter, such mount permitting an air-flow capacity between the perimetral edges of the closure and the face of the frame which is substantially greater than the air flow capacity through the said frame, when the closure is fully open.

11. A ventilator for doors or the like comprising a rectangular frame provided interiorly thereof with spaced apart light obstructing members, a closure extending across the face of said frame and movable to open or close the same, said closure having an area substantially greater than the frame but the air-flow capacity around the edges of the closure and between the latter and the surface of the said frame, when the said closure is fully open, being greater than the air-flow capacity through the frame, and pivoted closure operating means connecting the closure to the frame.

12. A ventilator for doors or the like comprising a frame provided interiorly thereof with spaced apart vision obstructing members, a closure disposed across the face of said frame for movement in parallelism with the frame-plane, pivoted means connecting the frame and the said closure serving to retain the latter in any position parallel to the face of the frame, and means permitting ready removal of the said closure from said connecting means to expose the spaces between said members.

13. A ventilator for doors or the like comprising a frame provided interiorly thereof with spaced apart vision intercepting vane members disposed in parallelism with sides of the frame, and a closure extending across the face of the latter and supported for movement away from said frame to any predetermined limit of separation from the frame, the dimensions of said closure being such that in any adjusted position of it within such

limit of separation from the frame a line of vision drawn across its edge through the frame opening will be intercepted by one or more of the said vane members.

- 5 14. A ventilator for doors or the like comprising a frame provided interiorly thereof with vision obstructing vane members, closure members capable of coacting with opposite faces of said frame, and mechanism operatively connecting said closure with the frame affording them movement in parallelism toward and away from the respective faces of the said frame.
